(57) **CLAIM**

The ornamental design for a mobile phone, as shown and described.

DESCRIPTION

FIG. 1 is a front perspective view of the mobile phone showing our new design;

FIG. 2 is a front view thereof;

FIG. 3 is a back view thereof;

FIG. 4 is a left side view thereof;

FIG. 5 is a right side view thereof;

FIG. 6 is a top plan view thereof;

FIG. 7 is a bottom plan view thereof;

FIG. 8 is back perspective view thereof; and,

FIG. 9 is an enlarged detail view of area 9 in FIG. 5.

The dash-dash broken lines depict portions of the mobile phone that form no part of the claimed design. The dot-dot-dash broken lines surrounding the area of the detail in FIG. 5 and FIG. 9 denote the boundaries of the enlarged detail and form no part of the claimed design.

1 Claim, 9 Drawing Sheets
